UNITED STATES PATENT OFFICE.

GEORGE M. MORRIS, OF COHOES, AND JOSEPH P. HALLENBECK, OF NEW YORK, ASSIGNORS, BY MESNE ASSIGNMENTS, TO THE NATIONAL MACHINE COMPANY, OF TROY, NEW YORK.

BUTTON-HOLE ATTACHMENT FOR SEWING-MACHINES.

SPECIFICATION forming part of Letters Patent No. 252,052, dated January 10, 1882.

Application filed July 30, 1879.

To all whom it may concern:

Be it known that we, GEORGE M. MORRIS, of the city of Cohoes, in the county of Albany and State of New York, and JOSEPH P. HALLENBECK, of the city, county, and State of New York, have jointly invented certain new and useful Improvements in Button-Hole Attachments for Sewing-Machines, of which the following is a specification, reference being had

to the accompanying drawings.

This invention relates to improvements in button-hole attachments for sewing-machines, by which the fabric having the button-hole therein is moved by a feed-foot or work-clamp longitudinally and transversely, so as to thereby present to the needle the whole edge of the button-hole upon the work-plate of a sewing-machine having its usual presser-foot and feeding device removed; and this invention is in some respects an improvement upon the button-hole attachment described in our specification of United States Patent No. 203,287, dated May 7, 1878. In the attachment described in that patent the cloth-clamp was carried by a feed-bar which was moved to and fro in ways to space the over-edge stitches by means of a pitman and crank-wheel which was revolved step by step by a reciprocating driving pawl acting on a ratchet-wheel of elliptic form, or of different diameters in different parts, so as to give to the crank-wheel different lengths of steps in different parts of its rotation to equalize the lengths of the steps imparted to the feed-bar by the crank-wheel and pitman. To produce a superior device for that purpose is the object of one part of this invention, which object we attain by the combination, with the movable feed-bar, crank-wheel, and pitman or its equivalent for connecting the feed-bar with the crank-wheel, of a second wheel geared with the crank-wheel and proportioned so as to revolve just twice to the crank-wheel's once, and a driving wheel or shaft eccentric to said second wheel and engaged therewith by a self-shifting crank-connection, so that the rotation of the said driving wheel or shaft by steps of uniform length shall rotate the said crank-wheel by steps of gradually-increasing length

through one-quarter of its revolution and of gradually-decreasing lengths through the next quarter, and so on repeatedly, and thereby cause the crank-wheel and pitman or its equivalent to move the feed-bar to and fro by steps of approximately equal lengths from one end to the other of such movements, and thus properly space the stitches.

Other parts of our invention relate to certain improved devices and combinations of parts for revolving the aforesaid driving wheel or shaft and operating the feed-bar, and for causing the movements of the latter to conform to the periphery of a button-hole, and for rendering the feed-foot capable of better holding and moving to and fro upon the needle-plate of a sewing-machine button-hole work or fabrics of greatly-different thicknesses, and of various thicknesses at opposite ends and sides of the same button-hole.

In the aforesaid drawings, in which similar parts are marked by like letters in the different figures, Figure 1 is a plan of a sewing-machine attachment which embodies this invention. Fig. 2 is a plan of the under side of a portion of the same above a horizontal section at the line *z z* in Fig. 9. Fig. 3 is a plan of a modified part of the same; Fig. 4, a vertical section thereof at the line *y y*, Fig. 3; and Fig. 5, a section of the same at the line *y' y'*, Fig. 3. Fig. 6 represents on an enlarged scale a button-hole having an eyelet-shaped end and surrounded by a row of over-edge stitches, which are arranged in about the same parallel directions all around the button-hole as they are made by this attachment, in combination with a common sewing-machine without its usual presser-foot and work-feeding device. Fig. 7 is a plan of the under side of a portion of the attachment shown in Fig. 1. Fig. 8 is a vertical section and elevation of the same at the line *x x* in Figs. 1, 7, 9, and 10. Fig. 9 is a section and elevation at the line *w w* in Figs. 1, 7, and 8. Fig. 10 is a section and elevation at the line *v v* in Figs. 1, 7, and 8. Fig. 11 is a section of a part at the line *u u* in Fig. 1. Fig. 12 is a side elevation of the work-feeding device, partly in section, showing its upper mem-

ber in full lines pressing on the work which rests upon a part of the work-supporting plate of a sewing-machine, and in dotted lines elevated from the work-plate. Fig. 13 is a front elevation, partly in section, of the same feeding device, with its upper member depressed upon the work; and Fig. 14, a front view of the same, showing the feed-foot elevated. Fig. 15 is a side view, and Fig. 16 an end view, of the journal which supports the depressing-cam that acts upon the upper member of the work-feeding device, and has an eccentric supporting-stem.

A is a bed-plate, which supports the other parts, and is to be secured by any suitable means to the frame or bed-plate of a sewing-machine so that the feed-foot B can bear properly upon the work-plate Z of the machine. Foot B is mounted upon the feed-bar C, which is formed to slide to and fro parallel to the lengthwise direction of the opening through the part B, in or upon a guide-plate, D; and the feed-bar is connected by a pitman, E, to a crank-pin, a, radially adjustable on the rotary crank-wheel F, so that by the rotation of the latter step by step the feed-bar will be moved step by step to and fro a distance regulated by the distance of the crank-pin from the center of the crank-wheel, substantially as described in the aforesaid patent No. 203,287.

In carrying out our present invention any suitable known equivalent for the pitman E can be used for imparting to-and-fro movements to the feed-bar from the crank-wheel.

G is a plate which is connected with the guide-plate D, and supported by ways b b' on the base A, so as to be movable to and fro and give reciprocating motion to the feed-bar C, to form the over-edge stitches, in a direction transverse to that in which the feed-bar is moved to and fro in or on its guide-plate D; and the plate G is connected by a self-adjusting stud, c, with a lever, H, which is pivoted at d to the plate A, and is adjustably connected by a link, H', with a lever, H'', that is pivoted at d' to the base-plate, and has a cam-follower, e', which is formed to engage with a suitable driving-cam on the sewing-machine, so that just after one withdrawal of the needle of the machine from its work-plate the feed-bar C will be moved forward a certain limited distance before the needle shall again enter the work-plate, and will be moved backward the same distance just after the next withdrawal of the needle from the work-plate, and so on repeatedly, all substantially the same as in the attachment described in the aforesaid patent. The guide-plate D is supported by ways e e' on the transversely-reciprocating plate G, and is also connected with the latter by a lever I, Fig. 7, engaging with a cam, J, fast on the crank-wheel F, which is carried by the plate G, whereby the plate D and feed-bar C, with its feed-foot B, in addition to being reciprocated transversely with the plate G to form the over-edge stitches, are, at the ends of the to-and-fro movements of the feed-bar, also moved in the same direc-

tion with but separately from the plate G, to thereby present the unstitched side of the button-hole to the needle, as described in the aforesaid patent. This device also embodies additional features, whereby the attachment is made capable of automatically presenting for stitching an edge having a varying course and a button-hole having an eyelet-shaped end. 75

K is a second wheel, engaging with the crank-wheel F by gear-teeth f g, the wheels being proportioned so that the wheel K must revolve just twice to the crank-wheel's once; and L is a rotary driver the axis of which is set eccentric to the axis of the wheel K, and said driver L is engaged with the wheel K by a self-adjusting crank-connection, M N, all arranged so that thereby the feed-bar C will be moved by the crank-wheel F and pitman E to and fro, 85 once each way, by steps of nearly equal lengths in all parts of the movements, by merely twice revolving the driver L by steps of equal lengths.

In carrying out our invention the rotary driver L can be in the form of a rotary ratchet wheel or shaft, as above stated, or any suitable known equivalent therefor. In constructing the attachment represented in the accompanying drawings we commonly have the driver L in the form of a crank-holding disk or wheel 95 mounted to turn on a stud, substantially as shown in Figs. 4 and 9.

In Figs. 1, 2, and 9 the crank-pin M is fast to the driving-wheel L, and has a follower, h, fitting in the radially-slotted guide N, which is fast on the wheel K; and in Figs. 3, 4, and 5 the crank-pin M is pivoted in the driving-wheel L, and has a slot, h', in which fits the guide N, that is fastened radially to the wheel K. The gear-wheel F has just twice as many teeth as the gear-wheel K, and those gears are so engaged with each other that whenever the pitman E is in line with both the crank-pin a and the axis of the wheel F, at which times the turning of the wheel F through a certain arc 105 gives the least movement to the feed-bar C, the crank-pin M on the driving-wheel L is then nearest to the axis of the wheel K, so that the then turning of the wheel L through a certain arc 110 gives the greatest length of rotary movement 115 to the wheel K, and thereby to the crank-wheel F, and the driving-wheel L being arranged properly eccentric to the wheel K, as indicated in the drawings, the revolutions of the wheel L by steps of equal lengths will cause the feed-bar C to be moved to and fro by steps of sufficiently uniform lengths to properly space the stitches from end to end of a button-hole. 120

With the above-described combination of the feed-bar C, pitman E, crank-wheel F, second wheel, K, geared to the crank-wheel to revolve twice to the latter's once, and wheel L, eccentric to the wheel K and engaged therewith by a self-shifting crank-connection, we have the reciprocating plate G constitute a part of the 130 driving mechanism, and have that plate support the wheels F, K, and L, feed-bar C, and feed-bar guide D, and connect the plate G with the feed-bar through that guide, and combine

with the part G the levers H H² and link H', for giving reciprocating motion thereto from a sewing-machine, and devices for imparting from the plate G step-by-step rotary motion to the wheel L.

For imparting from the reciprocating plate G step-by-step rotary motion to the wheel L when mounted on that plate we furnish that wheel with ratchet-teeth *i* and a concentrically pivoted lever, O, carrying a driving-pawl, *j*, engaged with the ratchet-wheel, and having the toothed arc *k* engaged with the toothed arc *l* on the lever P, that is pivoted at *l'* to the plate G, and is connected with the bed-plate A by a fulcrum-arm, Q, which is adjustable in guides *m m* by a screw, R, on the bed-plate. By this adjustability of the arm Q various lengths of uniform step-by-step movements can be given from the plate G to the wheel L, to make the steps in the movements of the feed-bar of proper length to space the stitches, whatever shall be the length of the reciprocating movement of the plate G, and of the to-and-fro movement imparted by the pitman E to the feed-bar from the crank-wheel.

The lever I, Figs. 7, 8, 9, and 10, engages by its follower *n* with the cam J on the crank-wheel F, and is pivoted by a stud, *o*, on a bracket, *o'*, that is part of or is fastened by a screw, *o²*, to the guide-plate D, and the lever I has a longitudinal slot, *p*, in which fits a fulcrum-stud, *p'*, that is fastened to the bar S, that is adjustable lengthwise in ways *p² p'*, by a screw, S', on the plate G, to alter the length of the movements imparted by the cam J, through the lever I, to the plate D, in respect to the plate G, much the same as in the attachment described in the aforesaid patent.

In case the button-holes to be worked shall have the two side edges straight and parallel throughout, the cam J and lever I can be shaped and engaged like the equivalent parts shown and described in the aforesaid patent, and we make the cam J of such shape that it will by the lever I give such lateral movements to the guide-plate D as to vary and change the course of the movements of the feed-bar, and thereby alter the course of the rows of stitches, as shall be required by the shape of the edges to be stitched. In Fig. 7 the cam J is shown shaped so that a button-hole having the course of its side edges in various directions, with an eyelet-shaped portion at one end part, will be so presented by the feed-foot B of the feed-bar to the needle of the sewing-machine that the edges of such button-holes having an eyelet-shaped end portion will be automatically bound all around by a row of stitches, *t*, substantially as indicated in Fig. 6. For feeding button-holes having side edges of various shapes, or eyelet-shaped ends of different sizes and forms, the cam J is to be made of corresponding different shapes in the proper parts of its circuit as shall be necessary in each case.

In Figs. 1, 12, and 13 a part of the feed-bar C is shown extended with an opening therein, through which the depressed foot B extends,

and freely presses and holds the button-hole work W against and slides it to and fro upon the usual work-supporting plate, Z, of a sewing-machine, as indicated in Figs. 12 and 13. This extension of the feed-bar around the foot B commonly helps that foot in properly holding and feeding soft thick fabrics, but is not generally used when stitching button-holes in leather and stiff fabrics. This extension of the feed-bar around the foot B is not essential to any part of our present invention, and we generally make that extension in a separate piece from the part of the feed-bar upon which the part B is mounted, as indicated in Figs. 10 and 12, and detachably secured thereto by screws, so that said extension-piece can be readily removed.

The foot B is mounted upon one end of a leaf-spring, T, which is fastened at its other end to an arm, U, that is hinged at *q* to a raised part, *q'*, of the feed-bar C; and V is a cam journaled upon a stud, *q²*, that is fast on or a part of the feed-bar, and extends through and above a perforation through the arm U, so that by turning down the cam V, as represented in Figs. 12 and 13, that cam will then bear upon and force down the rigid arm U, and thereby, through the spring T, press the foot B with an elastic pressure upon the button-hole work W on the work-supporting plate Z of the sewing-machine, as indicated in full lines in Figs. 12 and 13, and so that the elasticity of the spring T is not counteracted nor constrained by the rigid bearing down of the cam V upon the arm U, but is all exerted in pressing the feed-foot B with a yielding force upon the work on the work-plate of the machine. A spring, U', serves to elevate the arm U when the cam V is turned up, as in Fig. 10.

In order to provide convenient means whereby the foot B can be pressed down on the work upon the work-plate with various degrees of elastic pressure when the cam V is turned down upon the hinged arm U, as in Fig. 13, we mount the cam V on a journal, X, Figs. 1, 10, 15, and 16, having a stem, *r*, eccentric to the journal and fitting in a socket in the stud *q²*, and secured therein by a set-screw, *r'*, so that upon loosening that set-screw the journal X can be turned with and eccentrically to the stem *r*, and fastened by the screw *r'* with the journal at various different heights above the feed-bar, and so that when the cam V is turned down against the hinged arm U the latter will be depressed more or less, according to the adjusted height of the journal X, as shall be necessary or desirable to make the spring T give the proper strength of yielding pressure to the foot B upon work of various kinds or thicknesses.

By pressing down the hinged arm U more or less the spring T will be more or less bent, as indicated in Fig. 12, so as to thereby tend to correspondingly tilt up one side edge or the other of the foot B on the work W sliding on the sewing-machine plate, so that the foot will not press evenly upon the work along both side

edges of the button-hole. To overcome that difficulty we secure and pivot the foot B at its ends by longitudinal pivots s to the arms of a piece, Y, which is secured preferably by a transverse pivot-joint, s' , to an end piece, s^2 , on the spring T, so that the foot B will bear and press evenly upon the work on the sewing-machine plate along both sides of the button-hole, however much or little the spring T shall be bent or inclined by the different degrees of depression of the hinged arm U, which supports that spring on the feed-bar.

What we claim as our joint invention is—

1. In a button-hole attachment for sewing-machines, the combination, with the crank-wheel F, of a second wheel, K, proportioned and geared with the crank-wheel to revolve just twice to the crank-wheel's once, a rotary driver, L, having its axis eccentric to the axis of said second wheel, the self-adjusting crank-connection engaging said second wheel with said driver, and means for revolving said driver, all substantially as set forth.

2. The combination, with the crank-wheel F, second wheel, K, proportioned and geared with the crank-wheel to revolve twice to the crank-wheel's once, rotary driver L, eccentric to said second wheel, and self-adjusting crank-connection engaging said second wheel with the driver, substantially as described, of the ratchet i , driving-pawl j , and means for operating said driving-pawl, substantially as set forth.

3. The combination, with the feed-bar C, crank-wheel F, and means for imparting to-and-fro movements to the feed-bar from the crank-wheel, substantially as set forth, of the second wheel proportioned and geared with the crank-wheel to revolve twice to the crank-wheel's once, rotary driver eccentric to said second wheel, self-adjusting crank-connection engaging said second wheel with said driver, and means for rotating the latter, substantially as described.

4. The combination, with the feed-bar C, crank-wheel F, and means for imparting to-and-fro movements to the feed-bar from the crank-wheel, substantially as set forth, of the second wheel, K, proportioned and geared with the crank-wheel to revolve twice to the crank-wheel's once, rotary driver eccentric to said second wheel, self-adjusting crank-connection engaging said driver with said second wheel, ratchet i , pawl j , and means for actuating the latter, substantially as described.

5. The combination, with the feed-bar C, crank-wheel F, and means for imparting to-and-fro movements to the feed-bar from the crank-wheel, substantially as described, of the second wheel, K, proportioned and geared with the crank-wheel to revolve twice to the crank-wheel's once, rotary driver eccentric to said second wheel, self-adjusting crank-connection engaging said driver with said second wheel, and mechanisms for imparting step-by-step rotary motion to said driver and reciprocating movements to the feed-bar to form over-edge stitches, all substantially as set forth.

6. The combination, with the feed-bar C, crank-wheel F, and means for imparting to-and-fro movements to the feed-bar from the crank-wheel, substantially as specified, of the second wheel, K, proportioned and geared with the crank-wheel to revolve twice to the latter's once, rotary driver L, eccentric to said second wheel, self-adjusting crank-connection engaging said second wheel with said driver, plate G, means for operating the latter, and means for imparting step-by-step rotary motion to the driver L from the plate G, all substantially as set forth.

7. The combination, with the bed-plate A, plate G, means for operating the latter, and rotary driver L, of the ratchet i , lever O, having the pawl j and toothed arc k , lever P, having the toothed arc l , and the fulcrum-arm Q, mounted on said bed-plate, all substantially as set forth.

8. The combination, with the feed-bar C, crank-wheel F, and devices for imparting from said crank-wheel to the feed-bar to-and-fro movements to feed a button-hole lengthwise and movements transverse thereto to change the stitching from one side of the button-hole to the other, substantially as described, of the wheel K, proportioned and geared with said crank-wheel to revolve twice to the latter's once, rotary driver eccentric to the wheel K, self-adjusting crank-connection engaging said driver with the latter wheel, and means for rotating said driver, substantially as set forth.

9. The combination, with the feed-bar C, having standards q q^2 , and arm U, hinged to the standard q and carrying the feed-foot, of the depressing-cam V, cam-supporting pivot X, stem r , fast on and eccentric to said pivot, and fitting and adapted to be turned in a socket in the standard q^2 , and a screw, r' , by which the stem r can be fastened with the pivot X at various heights in respect to said socket, all substantially as set forth.

10. The combination, with the feed-bar C, having a standard, q' , arm U, hinged to that standard, and means for depressing said arm various degrees, substantially as described, of the part s^2 , spring T, fast at one end to said arm and at the other end to the part s^2 , forked piece Y, united to the part s^2 by pivot joint s' , and foot B, secured at its ends by pivots s to the arms of said forked piece, all substantially as set forth.

In testimony whereof we hereunto set our hands in the presence of two subscribing witnesses.
